UNITED STATES PATENT OFFICE.

BENJAMIN M. ROLPH, OF TAYLOR, ILLINOIS.

WINDMILL.

SPECIFICATION forming part of Letters Patent No. 234,204, dated November 9, 1880.

Application filed April 10, 1880. (No model.)

To all whom it may concern:

Be it known that I, BENJAMIN M. ROLPH, of Taylor, in the county of Ogle and State of Illinois, have invented a new and useful Windmill, of which the following is a specification.

This invention relates to that class of windmills known as "self-regulating mills," in which the wind-wheel is capable of assuming a position in a plane parallel to the lengthwise vertical plane of the main vane employed to hold the wind-wheel in the wind, in which position the wind will act upon opposite sides of the fan-blades on opposite halves of the wheel, and operate to retard its motion. To provide suitable mechanism capable of producing these results in a cheap and reliable manner is the object of this invention, and the devices employed, their application, and mode of operation will be hereinafter more fully described.

In the accompanying drawings, Figure 1 is an isometrical representation of a windmill embodying my invention, of which Fig. 2 is a plan view with the wind-wheel at right angles to the vane and in the wind. Fig. 3 is also a plan view in which the wind-wheel is parallel with the vane, in which position the mill is out of the wind. Fig. 4 is a rear elevation. Fig. 5 is a side elevation; Fig. 6, a central vertical section through the axial center of the shaft of the wind-wheel.

In the several figures A represents posts, which are rectangular in cross-section, of suitable size and connected at proper intervals by horizontal beams B, suitably framed or otherwise connected to the posts, producing a suitable tower in the form of a truncated pyramid having its truncated summit capped by a suitable table, C, and at a suitable distance below its summit is fitted with a transverse table,

D. These tables are provided with a vertical central opening, in which is fitted the vertical tubular bearing E, to receive the tubular shaft F to revolve therein. This tubular shaft F is connected with the mill, and by means of its tubular bearing serves to hold the mill in a vertical position on the tower to revolve in a horizontal plane for the purpose of permitting the mill to adapt itself to meet the changing directions of the wind.

G represents a wind-wheel of ordinary construction of the rosette form in which the fan-

blades are fixed. This wind-wheel is provided with a shaft, a, projecting from its center, and is fitted to revolve in a bracket-arm bearing, b, which rises from the side of the upper end portion of the vertical tubular shaft. The projecting end of this shaft a is fitted with a crank-head, c, provided with a wrist-pin, d, on which is journaled the pitman e, having its upper end pivoted to the vertical pump-rod f. 55 From the side of the tubular shaft opposite the bracket-arm bearing rises a bracket-arm support g, having its upper end portion, h, overhanging the axial center of the tubular shaft, and is fitted with a suitable opening to receive 60 the upper portion of the pump-rod f, and serves as a guide thereto to direct the up-and-down movements of the rod and to resist the sidewise action of the crank-head through its pitman-connection therewith. The upper open 65 end of the vertical shaft is fitted with a transverse bar, i, which is provided with a vertical opening through which the pump-rod slides in its vertical movements, and it operates as an additional guide and, in connection with 70 the overhanging guide-arm h, serves to retain 75 the pump-rod in proper position.

H represents the directing-vane which controls the horizontal movements of the mill, and its inner end is fixed to a vertical shaft, 80 k, which has its bearings fixed to the vertical support g in such a manner as to permit of a horizontal swinging movement of the wind-wheel through a quarter of a circle relatively with the vane in such a manner that the face 85 of the wind-wheel can move from a position in the wind, as represented in Fig. 2, at right angles to the vane, to a position out of the wind, as represented in Fig. 3, parallel to the vane.

At l is represented a miter-toothed quadrant-gear mounted on the vertical shaft with the directing-vane, and is connected therewith in such a manner that its horizontal movements shall be in unison therewith.

At I is represented a controlling-vane employed to control the velocity of the wind-wheel, and its inner end is fixed to a horizontal shaft, m, placed in substantially the same vertical plane with the shaft of the wind-wheel 90 and parallel therewith, supported in bearings projecting from the vertical support g. The

rear or projecting end of this shaft is fitted with a miter-toothed quadrant-gear, *n*, the teeth of which engage the teeth of the miter-toothed quadrant-gear *l*.

5 From this arrangement it will be seen that the vanes are placed at right angles to each other, and so connected that when the wheel is in the wind both vanes will be in parallel horizontal planes and in their relative positions at right angles to each other, as represented in Figs. 1, 2, and 4, and when the wheel is out of the wind the controlling-vane will be in the vertical position represented in Fig. 3, and will then, also, be at right angles with the directing-vane, but the vane-blades will then be in the same vertical plane with their edges to the wind, and as the wind-wheel is passing from the wind, or into the wind through the quarter of the circle in either direction from one point to the other, the controlling-vane will pass in one or the other direction from the horizontal to the vertical position, or vice versa.

From the foregoing it will be seen that when the mill is properly balanced to give a proper effective force under a given velocity of wind that an increased velocity of the wind acting against the controlling-vane will cause it to rise in a plane parallel to the face of the wind-wheel, and in such vertical movement, by means of its gear-toothed connection with the directing-vane, will carry the wheel out of the wind to a position parallel with the directing-vane, and as the velocity of the wind sinks the controlling-vane will descend toward its horizontal position and carry the wind-wheel into the wind. This action will vary with the varying velocities of the wind, and operates as a successful controlling device.

At *o* is represented a weight made adjustable on an arm, *p*, fixed to the arm of the controlling-vane, and is employed to hold the wind-wheel to the wind with greater or less force, as it is adjusted farther from or nearer to its center of motion.

45 At *s* is represented a counter-weight, made adjustable on an arm, *s'*, which is adjustably supported on the horizontal shaft of the controlling-vane, by means of which its relative angle with the arm *p*, on which the weight *o* is supported, may be varied, and in connection with the counter-weight *s*, made adjustable thereon, and the adjustable weight *o* furnish the means by which to adjust the mill to run with safety under any reasonable increase 55 of the velocity of the wind.

At *t* is represented a cord having its end portion fixed to the arm of the controlling-vane, or an arm connected therewith, from which it is passed upward over a pulley, *t'*, 60 suitably supported in bearings on the vertical standard *g*, and from thence down through the vertical tubular shaft *F* to a convenient posi-

tion to be operated from the ground. This cord is employed for the purpose of turning the wheel out of the wind when it is not required for use, which is accomplished by pulling the cord down to raise the controlling-vane to its vertical position and then fastening the cord in any convenient manner.

65 This mill is designed to be applied to any or most of the uses for which windmills are employed, and in its present form is fitted to be attached to a pump by means of the vertical central rod hereinbefore described as the pump-rod, and by means of which it may be connected to move machines of various kinds.

70 From the foregoing my invention and its operation will be fully understood without other or further detailed description.

75 I am aware that it is not new with me to provide the arm of the main vane with a segmental or quadrant gear which meshes with a segmental or quadrant gear pivoted to an upright arm on the turn-table, and hence I would have it understood that I make no broad claim 80 to such combination of parts.

I claim as my invention—

85 1. In a windmill, the combination, with the horizontal rotary shaft *m*, having an arm, *s'*, provided with a weight, *s*, connected therewith, of the arm of the controlling-vane *I*, secured to shaft *m*, said arm provided with arm *p* and weight *o*, substantially as set forth.

90 2. In a windmill, the combination, with horizontal rotary shaft *m*, having an independent arm, *s'*, secured in rotary adjustment on said shaft, and slide-weight *s*, attached to said arm, of the arm of the controlling-vane, attached to shaft *m*, said arm provided with arm *p* and weight *o*, substantially as set forth.

100

95 3. In a windmill, the combination, with the shaft *m*, having an independent arm, *s'*, secured in rotary adjustment on said shaft, and slide-weight *s*, attached to said arm, of the arm of the controlling-vane *I* attached to shaft *m*, said arm provided with arm *p* and weight *o*, and the arm of the directing-vane *H*, provided 105 with a quadrant-gear, *l*, and a quadrant-gear, *n*, attached to shaft *m*, substantially as set forth.

110

115 4. In a windmill, the combination, with shaft *m*, having the arm of vane *I* secured on one end thereof, of arm *s'*, provided with weight *s*, and located between said vane-arm and quadrant-gear and secured in rotary adjustment on the shaft-arm *p*, secured to the arm of vane *I*, and provided with weight *o*, and quadrant-gear *l*, attached to arm of vane *H* and meshing with quadrant-gear *n*, substantially as set forth.

BENJAMIN M. ROLPH.
